UNITED STATES PATENT OFFICE

HENRI ROCHAT, OF GENEVA, SWITZERLAND

ELECTRIC PLUG

Application filed June 18, 1930, Serial No. 462,078, and in Switzerland July 1, 1930.

My invention relates to an electrical plug provided with voltage controlling means and with a test lamp.

In the annexed drawings:

5 Fig. 1 is a vertical section of my plug, the lamp being supposedly removed.

Fig. 2 is a horizontal section of the same, the lamp being supposed in place.

10 Fig. 3 is a section on line X—X of Fig. 1.

Fig. 4 is a diagrammatic section on line Y—Y of Fig. 1, only the fixed parts being represented.

Fig. 5 is a similar sectional view, but only the movable parts being represented.

15 Fig. 6 is an end view of the plug.

Fig. 7 shows a glass plate adapted to be secured to the fixed parts.

Fig. 8 is a diagram of the electrical connections.

20 Fig. 9 shows the resistor of the plug before its winding in place.

The plug is provided with two pins 1 and 2 which are adapted to cooperate with a two-pin socket of any standard construction.

25 The electric current entering the plug through pin 1, for instance, is directed to a segmental member 3 which cooperates with a brush 4. The latter is connected with a terminal 4^b cooperating with another brush 4^a

30 to which is connected a wire 5 which leads to the socket 6 of the test lamp 7. This lamp is in turn connected to the external circuit

8, 9 from which the current is directed to the third brush 10^a contacting with a terminal

35 10^b, itself connected with a brush 10 cooperating with a segmental member 11 connected with the second pin 2.

A resistance 12 is connected in shunt with lamp 7.

40 In the position represented in Fig. 8, the current passes directly from the supply line to the external circuit the resistance of 12 and 7 being negligible. When the movable part 13 is rotated clockwise for one twelfth of a

45 turn (with respect to the fixed part 14), two portions 15 and 16 of a resistance are inserted in series in the circuit. By rotating part 13 for another twelfth of a turn, the inserted

50 resistance is increased, and so on up to a maximum for a rotation of 150°, when the

portions 15, 17, 19, 21, 23 and 16, 18, 20, 22, 24 are all inserted.

The resistance is formed by metallic wires wound on a mica support 25 as shown in Fig. 9 before its rolling in place. The lengths *a* 55 and *b* correspond to 150° when the resistance is in place on its insulating support 13. The latter is provided with studs 27 which are used to secure the mica plate 25 as shown in Fig. 3. A box or cover 29 is fixed to part 13 60 and rotatable with it and the resistance control is obtained by rotating box 29.

A push-button 30 with spring 31 is provided in the fixed part 14. A lateral finger 33 is fixed on this button, this finger cooperating 65 with depressions 34 in the movable part 13 to lock the latter at its successive correct positions.

The periphery of box 29 is milled at 36 to 70 make its hand-control easier. A glass plate 37 is fixed to the fixed part 14 and is provided with voltage indications cooperating with openings 38, 39 in the bottom of the box. The rotation of the latter is limited to 150° because the slit 40 in which depressions 34 are 75 provided, is itself limited to 150°.

When the indication 110 for instance, is in front of opening 38, no indication can be seen through opening 39. When box 29 is rotated clockwise for 30°, the indication 125 80 is seen through 39, no indication being in front of 38, and so on.

Ventilating holes 41 and 42 are provided.

The device is used to allow the connection of an apparatus on different supply lines. 85 When dealing, for instance, with an electric iron for hair-waving or other purposes, constructed for 110 volts, the latter may be used with lines at 125, 145, 190, 220 and 250 volts by rotating box 29 conveniently, the voltage 90 read on plate 37 being the voltage of the line. But the device is also useful to permit of controlling the current during use when needed.

I claim:

1. An electric plug comprising a fixed body having a cylindrical portion and means to be connected with the supply line; two segmental members on said portion each being connected with a pole of the supply line; a 100 rotatable annular member loose on said cylin- 100

drical portion; an annular resistance supported by said annular member, said resistance being divided into two halves insulated from each other; a pair of brushes carried by said annular member, adapted to cooperate with said segment member and connected each with one end of one half of said annular resistance, and said brushes being arranged at 180° from each other; a succession of terminals concentrically disposed on said annular member and connected with different points of said resistance in spaced and regular relation; a pair of brushes carried by said body and adapted to cooperate with said terminals, said brushes being disposed 180° apart from each other; and an external circuit connected in series with said brushes.

2. A plug as claimed in claim 1, wherein the rotation of the movable annular member is limited by a push-button locking device carried by the fixed body.

In testimony thereof, I affix my signature.
HENRI ROCHAT.
